UNITED STATES PATENT OFFICE

EDWARD C. MARQUA AND SAMUEL J. CALLAHAN, OF KANSAS CITY, MISSOURI

CEILING-ROD HANGER

Application filed January 26, 1927. Serial No. 163,679.

Our invention relates to hangers and more particularly to hangers for suspending ceilings from floors in concrete construction.

The object of our invention is to provide a hanger easily applicable to wooden mold forms for incorporation in a concrete floor, and also having features whereby the hanger can easily be secured with the ceiling elements.

10 We offer for accomplishing this object, a hanger comprising a member that may be inserted through an aperture in a form board before the concrete is poured and will be retained in position by an anchoring member, 15 both members to be embedded in the poured concrete but not interfering with the removal of the form after the concrete has set. Our device, further, offers a means of easy and quick attachment of a hanger to the 20 channel iron cross bars that ordinarily provide and constitute the ceiling framework and for the support of which a device such as that which we now offer is necessary, since the cross bars cannot be stapled or nailed to 25 the concrete beams.

The features and functions of our device will be more particularly described with references to the drawings in which:

Fig. 1 is a perspective view of a concrete 30 floor form and concrete floor partly laid, equipped with our invention.

Fig. 2 is a cross section of concrete floor and of examples of our device whereby a ceiling is suspended.

Fig. 3 is a perspective view of an anchor plate member of our device.

Fig. 4 is a view of a section of concrete floor and our device embedded therein.

Fig. 5 is a side elevation of the device installed in a wooden form shown fragmentarily and in cross section.

Referring in detail to the drawings:

The device comprises an anchor plate 1, bent in the shape of an inverted V, that is, lambdoid, and having an aperture 2, and a short piece of wire constituting a hanger rod 3 to be received by the anchor plate 1 through the said aperture and provided with a hook portion 4 for engagement with one of the flaring sides of the plate. The device is de-

signed for installation in a wooden form 5, the horizontal mold board member 6 thereof being provided with suitable orifices 7 for the insertion of the rods 3 upon erection of the form in preparation for the deposit on the form of the concrete floor 8. The installation of the device assumes the insertion of a rod in a plate, and then the inserting of the rod in a horizontal member 6, the depending rod, its lower end projecting below the form, being restrained by the engagement of the hook portion 4 with the V-shaped plate that rests on the member 6.

The flowable concrete mixture poured upon the form flows into the recess 9 produced by the juxtaposition of the bent plate with the form, and there hardening provides a bracket or lock 10, comprising an arm or loop offered by the hardening body of concrete and integral therewith for supporting the device upon removal of the form.

A particular feature of our invention is comprised in the structure and arrangement whereby the device supportable as suggested, remains undisturbed and without reduction of its efficient engagement with the concrete floor upon such removal of the form, the horizontal member 6 being withdrawable vertically from contact with the rod 3 and the plate 1. The surface engagement of the concrete with the plate provides also a supporting factor.

The form having been removed and the rods depending from the self-supported concrete floor, channel iron cross bars 11, constituting running bars, and furring channels 11^a, are provided, and the running bars are secured to the depending devices by means of hooks 12 produced on the ends of the rods 2 whereby the devices support the running bars from the concrete floor. The furring channels, which are shown as channel irons and may be rods, are similarly suspended and secured by rods 3, or they may be supported by the running bars through wiring engagement therewith. The ceiling 13 is then installed, comprising metal lath 14, elements of which are disclosed in cross section in Fig. 2, which are spaced from and secured to the cross bars and the furring channels by 100

wires 15, and ceiling plaster 16 which is applied to the lath.

It is apparent that as many of the devices may be installed as desired, and in such locations and with such lengths of depending wire hanger rods as may be estimated for the attachment thereto of suitable cross bars for the support of ceiling elements. It is also apparent that our device provides convenient and flexible means of meeting emergencies disclosed in the requirements for ceiling construction after the completion of the concrete floor, and also for solving incidental problems as to hanging factors connected with the ceiling.

Particular attention is called to the freedom conferred on our device by its structure from a usual and serious hazard common to ceiling hangers. The ordinary wire hanger rod provided with a loop seatable on a form when the rod is projected through the form, offers an example. The loops often become displaced and when the concrete is laid the loops are not securely embedded in the concrete to support weight that may be attached to the rod. The result is often the pulling of the hanger away from the concrete flow in process of attaching the running bars, a more serious delayed result being the falling of the ceiling. Our device assures an adequate support, since the bent plates cannot be distorted appreciably by heavy pressure and are not subject to lateral disturbance.

We may provide means of elevating the plates from the surface of the horizontal members of the form, and may install devices also at other locations for embedment in the beam members of the concrete floor.

We have described the hanger as used with wooden joist molds. It is obvious that it may be used in connection with steel joist molds. It may also be employed for suspending ceilings under any other type of reinforced concrete floor construction.

Other variations in use, and analogous modifications of form, will appear as suitable to meet different conditions, which may be employed without departing from the spirit and general disclosure of this application.

What we claim and desire to secure by Letters Patent is:

1. A ceiling supporting member projectible through a form board having a head located above the form board, and an anchoring member supported on the form board and adapted to receive the supporting member for supporting the head above and out of contact with the board to permit embedment of the head in concrete poured onto the board.

2. A ceiling supporting rod having a hook located above a form board, and an anchoring member having an opening to receive the rod for supporting the hook out of contact with the board to permit embedment of the hook in concrete poured onto the board.

3. A ceiling supporting member projectible through a form board having a hook located above the form board and an open ended lambdoid plate supported on the form board having an opening through which the said member projects for supporting the hook out of contact with the form board to permit embedment of the hook in concrete poured onto the form board.

4. A ceiling supporting rod projectible through a form board having a hook located above the form board, and an inverted V shaped plate supported on the form board having an aperture in its apex through which the rod projects, for supporting the hook to permit embedment of the hook in the concrete poured onto the form board.

In testimony whereof we affix our signatures.

EDWARD C. MARQUA.
SAMUEL J. CALLAHAN.
